ROTARY WING AIRCRAFT

Edward A. Stalker, Bay City, Mich.

Application September 7, 1944, Serial No. 553,682

10 Claims. (Cl. 170—135.4)

1

My invention relates to direct lift aircraft and particularly to jet propelled lifting rotors. It has for an object the provision of an efficient means of propulsion wherein more air is discharged on the advancing side of the orbit than on the retreating side when in horizontal flight. Another object is to provide a means of changing from the condition of uneven discharge about the orbit to uniform discharge for hovering flight.

Still another object is to provide a cam means which prescribes a pattern of action for changes of blade pitch superimposed on another pattern of action resulting from a first cam means. Other objects will appear from the specification and drawings.

I accomplish the above objects by the means illustrated in the accompanying drawings in which—

Figure 1 is a side elevation of a helicopter;
Figure 2 is a fragmentary top plan of a blade;
Figure 3 is a section along the line 3—3 in Figure 2;

Figure 4 is a fragmentary plan of the mechanism to operate the auxiliary flap;

Figure 5 is a fragmentary elevation of the hub part of the mechanism of Figure 4 on line 5—5 of Fig. 4;

Figure 6 is a fragmentary vertical section 6—6 of Figure 2 showing the manner in which the blade root forks are fastened to the hub;

Figure 7 is a top fragmentary view of the rotor hub and part of the flap actuating mechanism;

Figure 8 is a side view of the elements of Figure 7; and

Figure 9 is a top fragmentary view of the wing, flap and actuating mechanism in the region 9—9 of Figure 2.

When a helicopter is hovering or climbing vertically in still air the magnitude of the velocity of the relative wind is the same for the blades in all positions about the axis of rotation. If the blades are being rotated by a jet discharged downstream from the blades equal quantities may be discharged from a slot in each blade. If the slot is in a portion of the surface so as to affect the lift coefficient the jet should be the same for various orbital positions of the blade as regards volume and speed.

If the helicopter is moving forward, the relative wind has a slower velocity past the retreating blade than past the advancing blade. If the jet is relied upon to change the lift coefficients of the blades there should be a dissymmetry in the jets as regards volume and speed. It has always been assumed previously that the jet lift effect should

be largest for the retreating blade so as to support it. This will be shown to be undesirable for the aircraft herein described. If the blade is equipped with a slot in its upper surface it is possible to support the retreating blade by increasing its lift by a jet out the slot. Especially if the jet effect is combined in a special manner with a flap the quantity and/or the speed of the jet can be greatly reduced. It is in fact desirable to reduce the energy of the jet to a minimum because when the type of flap to be described is depressed the jet is directed downward rather than rearward. Hence a large part of the propulsive effect of the jet is lost. It is therefore desirable to reduce the energy of the jet of the retreating blade to the amount just necessary to obtain the increase in lift coefficient in conjunction with the flap and to increase the total energy of the jet out of the advancing blade to provide the main propulsive force to rotate the lifting rotor and propel the aircraft forward.

In forward flight the retreating blade is subjected to a reduction in relative wind speed and hence it is possible to reduce the volume of the jet as compared to the advancing blade. The required energy of the jet for lift augmentation by boundary layer control is proportional to the energy of the relative wind. On the retreating blade the relative wind velocity is low, requiring therefore only a small jet energy.

In order that the advancing blade does not generate too much lift (and be forced against the limit stops in vertical flapping) the blade flap must be raised on the advancing blade.

The mode of operation of the rotor blade consists in lowering the flap on the retreating blade and restricting the flow out of the jet while raising the flap on the advancing blade and enlarging the flow out of its slot to propel the blades.

In vertical flight the blade flaps are to be depressed not at all or preferably only slightly so that the jets exert substantially their full effect in propelling the blades.

One of the devices described herein is a means for cyclically varying the amount of air blown from the slot of a jet driven helicopter rotor blade while the machine is in forward flight, and for providing a uniform air flow from the blade when the machine is hovering. The cyclic change in air flow is from a high to a low quantity of discharge. The uniform air flow discharges at an intermediate rate.

The change in amount of airflow is accomplished by varying the width of the slot exit through the agency of a small rotatable flap

which forms one side of the slot. The cyclic change is such that a large amount of air is discharged through the widened slot while the rotor blade is on the advancing side of its orbit, and a small amount of air is discharged through the narrowed slot on the retreating side of the blade's orbit.

The helicopter of Figure 1 has the rotor blade 1 supported from the hub 2 and free to flap vertically about the axis 2a. The blade is equipped with the main flap 3 and the auxiliary flap 4. Each blade is attached by the fork 1a to the hub to be revolved about a vertical axis. As shown in Figure 3 the main flap has an upper contour of radius R so that rotation of the main flap about the hinge at the origin of the radius does not vary the slot between the auxiliary flap 4 and flap 3.

The rotor is revolved by a jet of air emitted from the passage 5 through the slot 6 rearward along the surface of the flap. This type of propulsion has been described in more detail in my U. S. Patent No. 2,084,464. Air is forced into the hub by power means and flows to the slot via the duct 5 formed by the blade walls.

The helicopter can be propelled more efficiently by discharging most of the jet from the advancing blade than by discharging it equally about the orbit. The efficiency of propulsion is a function of the ratio of jet speed V_j to blade speed V_R as indicated by the following equation

$$\eta = \frac{2}{1 + V_j/V_R}$$

Since the advancing blade has a velocity V_R equal to the sum of the rotational and translational speed, the sum can more nearly approach the jet velocity V_j .

From another point of view it may be observed that the jet from the advancing blade both rotates the rotor and propels the helicopter forward.

The emission of the jet mainly from the advancing blade greatly increases the efficiency of propulsion of the whole machine.

The auxiliary flap 4 which is hinged at 8 is raised on the advancing blade to increase the opening of the slot and it is lowered on the retreating side to decrease the slot opening. The slot width should be varied rapidly when the blade is near the front and back positions. This is accomplished by the variable displacement means incorporating the cam plate 10 whose cam groove 9 accommodates the end of arm 7 attached to the flap 4. The cam plate is slideable on the rollers 11 and when such motion takes place the arm 7 is moved to rotate the auxiliary flap.

The motion of the cam plate 10 is referred to the orbital position of the blade about the upright axis by means of the cam 12 and suitable mechanism connecting it to the cam plate.

Cam 12 is attached rigidly to shaft 13 which is in turn fixed rigidly to the aircraft structure. Plate 14 is part of the hub to which the helicopter blades 1 are attached and is free to rotate on bearings 15. Fork 16 which is part of plate 14 supports fork 17 on the axis 18. Fork 17 is an integral part of arm 19 which is caused to oscillate around axis 18 by roller 20 riding in the slot of cam 12. Fork 21 is pinned to nut block 22 at one end and at the other to slide rod 22a which slides in sleeve 22b supported on arm 22c which is part of plate 14. Slide rod 22a actuates flexible push-pull or Bowden cable 23 which transmits spanwise motion to slide rod 23a and in turn moves cam plate 10. Slide rod 23a is supported by sleeve 24 which is fastened to the blade struc-

ture. The blade 1 is free to swing vertically around horizontal hinge 2a which causes sleeve 24 and slide rod 23a to move up and down relative to slide rod 22a. Flexible Bowden cable 23 permits this relative vertical motion without affecting the spanwise positions of either slide rod 22a or 23a. Rollers 11, supported by the blade structure, allow cam 10 to slide spanwise. Link 25 connects a plurality of cams identical to 10 distributed along the span. Nut block 22 can be moved so that axis 18 can be moved from position A to position B by revolving screw 27. Screw 27 is turned by pinion 28 mating with rack 29. Universal joint 30 fastened to rack 29 lies on axis 18 so that oscillation of arm 19 will not affect the vertical position of rack 29. Link 31 is moved by arm 32 which is pivotally supported by fork 33. They revolve with hub 14 around shaft 13. Grooved sleeve 34 does not revolve on shaft 13 but is free to slide vertically by the action of bell-crank 35 and link 36. The last is attached to a control operable by the pilot.

For forward flight, nut block 22 remains fixed at the outer end of crank 18 and oscillates between positions A and C by the action of roller 20 in cam 12. Cam 10 is thereby caused to reciprocate moving roller 9 and arm 7 causing flap 4 to move from position D to F and back.

As the rotor blade revolves around its orbit from G to H (see Fig. 4 of which direction GK is forward) the flap 4 opens from F to D (see Fig. 3). As the blade revolves from H to I to J the flap 4 remains wide open. Revolving from J to K the flap 4 closes down again to F and remains there while the blade revolves to L and then to G.

In hovering flight nut block 22 is moved from position A to B with the screw 27. Position B is on axis 18, therefore the oscillation of crank arm 19 imparts no motion to link 21. The geometry of point B relative to A and C is such that cam 10 is held at an intermediate position putting flap 4 into fixed position E.

A like type of mechanism is used to control the angular position of flap 3 as for flap 4.

45 The ring 60 is tiltable universally and for a given attitude of tilt determines a displacement about its perimeter of roller 62 which is sinusoidal. The displacements on opposite sides of the axis of rotation are opposite but of equal magnitude. This means that with direct connection to the flap that it would be moved through equal angles. This will not be desirable for substantial advance ratios. This may be noted from the fact that as the forward speed increases less of the 55 retreating blade is lifting while all of the advancing blade continues to lift. Hence it is desirable to have a different variation of flap displacement around the orbit than provided by the sinusoidal function of the ring 60. A mechanism 60 to give a different variation will now be disclosed.

A suitable linkage enables the pilot to tilt control ring 60 which imposes a cyclic motion on blade flap 3. The motion is such that flap 3 is up to position D' (Fig. 3) on the advancing side 65 of its orbit and down to position F' on the retreating side of its orbit.

The relationship of positions between flap 3 and slot flap 4 during forward flight is that on the advancing part of the blade's orbit, flap 3 is up to D' reducing the lift coefficient while slot flap 4 is wide open to position D permitting a large volume of air discharge contributing direct thrust to the aircraft as well as creating torque on the blades. The lift coefficient is reduced because of the high relative speed of the advancing

blade. On the retreating side of the blade's orbit, flap 3 is down to position F' and slot flap 4 is down to position F discharging only enough air to create a high lift coefficient. For hovering and climb conditions flap 3 remains at or near position E' and slot flap 4 remains at position E throughout the blade's orbit.

Ring 60 is mounted on spherical sleeve 64 with balls enabling it to be tilted about any horizontal axis by rods 66 and 68 displaced 90° to one another. As the blades rotate, roller 62 revolves with them but rides between flanges on ring 60 and is therefore forced up on one side of its orbit and down on the other depending on the amount of tilt given to ring 60.

As roller 62 moves up and down link 70 oscillates crank 72 which moves link 74 oscillating crank 76 and push-pull rod 78. Rod 78 is connected by universal joint 79 to splined shaft 80. This shaft 80 carries the roller 82. See Figure 9. Splined shaft 80 is prevented from revolving by splined sleeve 84 attached to the blade structure. As roller 82 moves in and out, cylindrical cam 86 fastened to flap 3 is caused to revolve thereby moving the flap.

Tilting of control ring 60 displaces roller 62 up on one side and down an equal amount on the other. Crank 72 however is arranged to give differential motion to the succeeding linkage to roller 82. This differential motion added to the differential action of cam 86 causes the flap 3 to revolve down on the retreating part of its orbit a great deal more below position E' than it revolves above position E' on the advancing side of its orbit. The flap 3 reaches position E' when the blade's orbital position is ahead and behind the upright axis of rotation in forward flight.

Uniform control of the blades regardless of their orbital positions (necessary for hovering and climbing) is accomplished by vertical sliding of sleeve 64 by rod 88 which elevates ring 60 without tilting it thereby giving uniform motion to the flap actuating linkages. Sleeve 64 slides on cylinder 89 which is an integral part of hub 14.

A depression of flap downward is equivalent to a change in pitch of the blade. It is in fact a change in the effective pitch of the flap portion of the wings.

A movement of the flap 4 causes both a change in propulsive effort and a change in lift of the blade.

The width of the plan form of the blade increases to the inner end of the flap to provide a low velocity at the locality where the flap would tend to restrict the flow. In other words since the flap does not conduct flow within the blade, its presence deletes part of the duct cross section.

I have now described suitable embodiments of my invention which are now preferred. It is to be understood however that the invention is not limited to the particular construction illustrated and described and that I intend to claim it broadly as indicated by the scope of the appended claims.

I claim:

1. In combination in a helicopter, a blade rotatable about an upright axis, variable thrust producing means on said blade, means for varying the lift of said blade, and control means for controlling the force exerted on said blade by said thrust producing means and for controlling the action of said lift varying means to vary said force and said lift cyclically and inversely during blade rotation.

2. In combination in a helicopter, a blade rotatable about an upright axis, means to vary the lift of said blade, jet thrust producing means for said blade including a variable discharge slot in said blade forming means to vary the force of said jet, and cyclically operative control means for decreasing the lift of said blade and increasing the force of said jet in the advancing position of rotation of the blade.

3. In combination in a helicopter, a blade rotatable about an upright axis, means to vary the lift of said blade, jet thrust producing means for said blade including a variable discharge slot in said blade forming means to vary the force of said jet, and cyclically operative control means for decreasing the lift of said blade and increasing the force of said jet in the advancing position of rotation of the blade, said control means incorporating means for effecting a rapid change in the force of said discharge jet when said blade nears its front and back positions.

4. In combination in a helicopter, a blade rotatable about an upright axis, means to vary the lift of said blade, jet thrust producing means for said blade including a variable discharge slot in said blade, adjustable control means operable cyclically for decreasing the lift of said blade and increasing the force of said discharge jet in the advancing position of said blade during forward flight, and means for adjusting said control means to maintain a substantially uniform force of said discharge jet during vertical flight.

5. In combination in a direct lift aircraft, an adjustable pitch blade supported for rotation about an upright axis, thrust producing means for said blade including a spanwise passage therewithin, means forming a slot in the upper surface of the blade leading out of said passage adapted to discharge a fluid jet, the walls of said slot being formed to direct the jet fluid toward the blade trailing edge substantially along the blade surface, means to control the volume of said jet to vary the thrust produced thereby, means to increase the effective pitch of said blade while in the retreating position and decrease the effective pitch while in the advancing position of rotation, and means for actuating said volume control means to increase the jet flow in advancing positions of blade rotation over the jet flow in retreating positions of blade rotation.

6. In combination in an aircraft, a hollow blade rotatable about an upright axis, thrust producing means for said blade including a slot in the surface thereof leading into the blade interior and adapted to discharge a propulsive jet to rotate said blade about said axis, said blade having a flap, means for adjusting said flap to increase the lift when the blade is in a retreating position and to decrease the lift when the blade is in an advancing position, means for varying the discharge opening of said slot to control said propulsive jet, and means to control said slot varying means to discharge the greater jet volume through the slot of the blade in the advancing position of rotation.

7. In combination, a fuselage, a blade supported on the fuselage for rotation about an upright axis, said blade having an adjustable flap rotatable relative to the blade main body about a spanwise axis from a normal position substantially in trailing alignment with said main body, thrust producing means for said blade including a discharge slot in the upper surface thereof leading out of the blade interior to discharge a fluid jet to rotate the blade about

said upright axis, means to control the flow through said slot, means to rotate said flap downward on the retreating blade to a greater degree than the flap is rotated upward on the advancing blade from said normal position, and means actuating said flow control means for decreasing the volume of flow through the slot of the blade in the retreating position of rotation thereof relative to the volume of flow through the slot of the blade in the advancing position of rotation thereof.

8. In combination in a helicopter, a hollow wing rotatable about an upright axis, said wing having a slot in its surface leading out of the wing interior, means for discharging through said slot a jet flow to propel the wing about said axis, means to control the flow through said slot, said wing having a flap, means to rotate the flap downward to increase the wing lift, and means actuating said flow control means coincidentally with said flap means rotating said flap to wing lift increasing positions to decrease the volume of flow through said slot.

9. In combination in an aircraft, a blade main body, an adjustable main flap supported at the rear of said body to form a blade and leaving an opening therebetween into said blade interior, means supporting said blade for rotation about an upright axis, a flow control flap, means for adjustably supporting said flow control flap at its front edge on said main body to extend in overlying relation with respect to said main flap and said opening, the rear edge of said control flap being normally spaced from the surface of said main flap to form a slot having communication with said blade interior through said opening, means to displace said main flap downward while maintaining a preassigned width of said slot, means operable independently of said displacing means to adjust the position of said control flap to alter the width of said slot, and

means to cause a flow of fluid through said slot.

10. In combination in a helicopter, a blade main body, an adjustable main flap supported at the rear of said body to form a blade and leaving an opening therebetween into said blade interior, a flow control flap, means for adjustably supporting said flow control flap near its front on said main body to extend in overlying relation with respect to said main flap and said opening, means supporting said blade for rotation about an upright axis, the rear edge of said control flap being normally spaced from the surface of said flap to form a slot in communication with said blade interior through said opening, means to rotate said main flap downward, the upper surface of said main flap being formed with a radius of curvature so that said upper surface has a substantially constant distance from the rear edge of said control flap during rotation of said main flap to provide a substantially constant slot width, means to adjust the position of said control flap to vary said slot width, and means to cause a flow of air through said slot.
